UNITED STATES PATENT OFFICE.

ALBERT BIE, OF WINTERTHUR, SWITZERLAND, ASSIGNOR TO BUSCH-SULZER BROS.-
DIESEL ENGINE COMPANY, OF ST. LOUIS, MISSOURI, A CORPORATION OF MISSOURI.

ENGINE CONSTRUCTION.

1,260,861.

Specification of Letters Patent. Patented Mar. 26, 1918.

Application filed June 17, 1915. Serial No. 34,582.

To all whom it may concern:

Be it known that I, ALBERT BIE, a subject of the Kingdom of Norway, residing in Winterthur, Canton of Zurich, Switzerland, have invented certain new and useful Improvements in Engine Construction, of which the following is a full, true and complete specification.

The invention relates to internal combustion engine construction embodying improvement in the assemblage and manufacture of the combustion cylinder and special facilities for cooling the same and accommodating the thermal expansions and contractions, as will hereinafter be made apparent to those skilled in the art.

In the accompanying drawings:

Figure 1 is a vertical section through the head end of a cylinder containing the improvement in one of its forms;

Fig. 2, a plan thereof;

Fig. 3, a fragmentary vertical section of another form;

Fig. 4, a horizontal section on the line 25 IV-IV of Fig. 3; and

Fig. 5 is a view of the engine, partly in elevation and partly in vertical section.

The water-jacket 1 is provided at its head end with four lateral lugs 13, which are 30 clamped to the upper ends of tie rods or columns 2 rising from the base 14, and its lower end is provided with similar guide lugs 15 also engaged to the rods and capable of movement thereon to accommodate lengthwise expansion of the water-jacket wall. The water jacket cylinder is thus relieved of longitudinal stresses and its head bearing the valve organs is held in fixed position with relation to the crank shaft 36 under 40 all conditions.

The upper portion of the water-jacket which is swelled outward, as shown at 16 is formed with a depending, reversely-turned inner wall 17, forming the circular boundary of a head-receiving recess, and the lower end of this wall, being appropriately braced as indicated, forms an annular seat 8 to receive an outwardly directed head flange 19 on the upper end of the cylinder liner 6.

50 The latter is a separately made part intended to complete the water jacket and surround the combustion space and the reciprocating piston 20. At its lower end the liner 6 is fitted to the water jacket in any suitable

manner, which will retain the cooling water 55 and accommodate such difference of expansion as may occur.

The head 3 is hollow for circulation of water, entering at 3^a and leaving at 3^b, and is intended to carry the usual valve organs, 60 as indicated by the valve sockets 4. This head is set into the upper end of the water-jacket, bearing against the top of the head flange of the liner, with which it forms a tight seal against leakage from the combustion space, by means of interengaging facings 7, with or without a gasket. The top of the head is formed with an outwardly extending flange 21 overlying the top of the water-jacket, to which it is fastened by bolts 70 5. These bolts press the head and the liner flange together and against the seat 8, and, being entirely independent of the tie rods 2, permit the ready removal of the head without disturbing the columns 2 or disconnecting therefrom the cylinder part 1. The liner 6 can also be readily withdrawn if desired when the head has been removed.

The liner flange 19 is preferably recessed, as indicated at 9, in order that it may be 80 cooled by access of the cooling water to its interior, and the recessing of the flange may be in the form of a continuous annular groove recess, as shown in Fig. 4, or of separate cavities, as suggested in Fig. 1; and in 85 either event the interior of the flange may be placed in communication with the water-jacket space by openings 10 through the wall 17, above the seat 8. Furthermore, as shown in Figs. 3 and 4, openings 12 may pierce 90 the under side of the head flange, opening into the water jacket space below the seat. In this construction the upper portion of the water jacket space is preferably divided off, either partially or entirely, by a wall 22 95 connecting the lower edge of the wall 17 with the outer wall of the water-jacket, thus facilitating the circulation of water from one part of the water-jacket space to another and through the interior of the flange 100 19. The lip 11 in Fig. 3 obstructs escape of water through the crevice between the head and water jacket.

From the foregoing description it will be apparent that the principle of the invention is not confined to the specific construction above described, and that various modifications, changes in proportion and alterations

may be made therein without departing from the scope of the following claims.

I claim:

1. An internal combustion engine comprising a base, a set of tie rods rising therefrom, a combustion cylinder having a water-jacket between said rods and detachably secured to the latter by its upper end, and a cylinder head fastened to the cylinder independently of the tie rods and removable without disturbing the connection of the cylinder thereto.
2. An internal combustion engine comprising a base, a set of tie rods rising therefrom, a combustion cylinder having a water-jacket between said rods and detachably secured to the latter, a cylinder head having a cylindrical hollow body set within the upper end of the cylinder and a downwardly facing shoulder at its top, and bolts passing through said shoulder into the cylinder end and permitting the removal of the cylinder head without disturbing the connection of the cylinder with the tie rods.
3. In an internal combustion engine, the combination of a base, a set of tie rods rising therefrom, a water-jacket between and detachably secured by its upper end to said tie rods, a separate cylinder liner terminating at its upper end below the top of the water-jacket, a cylinder head comprising a cylindrical hollow body set into the upper end of the water-jacket against the end of the cylinder liner, and bolts holding the cylinder head in place and permitting removal of the same outwardly through the top of the water-jacket.
4. In an internal combustion engine, a water-jacketed cylinder detachably connected by its upper end through tie rods with a base plate and having its head portion constituted of outer and inner parts, the outer of said parts being integral with the water-jacket and the inner part being fastened independently of the tie rods and removable outwardly from the top of the cylinder.
5. In an internal combustion engine, the combination of a base, a set of tie rods rising therefrom, a water-jacket between and secured by its upper end to said rods, said water-jacket having a seat below its upper end, a cylinder liner having a flange resting on said seat, a cylinder head comprising a cylindrical hollow body set into the upper end of the water-jacket and bearing against the end of the cylinder liner, and means separate from the tie rods for pressing the cylinder head and liner against said seat.
6. In an internal combustion engine, a water-jacket having an inner wall at its head end forming an inner boundary of the water-jacket space, and a seat on said wall inwardly of the end, a cylinder liner having a flange against said seat, a cylinder head comprising a cylindrical hollow body set into

said inner wall bearing against the end of the liner and having a flange at its outer end overlying the end of the water-jacket, said head and the liner flange being formed with interengaging joint members, and bolts 70 passing through the flange of the head into the water-jacket and forcing the said joint members together and the flange of the liner against its seat.

7. In an internal combustion engine, a 75 water-jacket having a seat inwardly of its head end, a liner having a flange bearing against said seat, a head comprising a cylindrical hollow body set into the water-jacket and bearing against the liner flange, and 80 means engaging the head for pressing the same and the liner flange to the seat, said head and liner being free for radial expansion in the water-jacket.

8. In an internal combustion engine, a 85 water-jacket having a seat inwardly of its head end, a liner having a flange bearing against said seat, and lateral passages in the wall of the water jacket affording access for the cooling water to said liner flange. 90

9. In an internal combustion engine, the combination of a water-jacket having a seat inwardly of its head end, a liner having a recessed flange bearing against said seat, a head set into the end of the water-jacket 95 and bearing against said flange, and openings in the water-jacket placing the water-jacket space in communication with the interior of the liner flange.

10. In an internal combustion engine, the 100 combination of a water jacket having an inner wall spaced from its outer wall at its head end portion, said inner wall being formed with an inwardly projecting seat and with openings adjacent said seat, a cylinder 105 liner having a recessed flange resting on said seat and in communication with said openings, and a head set into the inner wall of the water-jacket and holding the liner flange against its seat. 110

11. In an internal combustion engine, the combination of a water-jacket having an inner wall spaced from its outer wall at its head end portion, said inner wall being formed with an inwardly projecting seat and 115 with openings adjacent said seat, and a cylinder liner having a recessed flange resting on said seat and in communication peripherally with said openings, the flange also having openings through its under side into 120 the water-jacket space.

12. In an internal combustion engine, the combination of a water-jacket having an inner wall at its head end portion and a division wall connecting the said inner wall 125 with the outer wall of the water-jacket, said inner wall having an inwardly projecting seat and openings above said seat into the portion of the water-jacket space between said outer and inner walls, a cylinder 130

liner having a hollow flange bearing against said seat and communicating on the one hand with said openings and on the other hand with the main water-jacket space, and a head set into the inner wall of the water-jacket and holding the liner in place.

In testimony whereof, I have signed this

specification in the presence of two witnesses.

ALBERT BIE.
